UNITED STATES PATENT OFFICE.

THOMAS A. CARVER, OF COLO, IOWA.

DESIGN FOR A DUST-PAN.

50,123.

Specification for Design.

Patented Jan. 2, 1917.

Application filed September 1, 1916. Serial No. 118,155. Term of patent 3½ years.

To all whom it may concern:

Be it known that I, THOMAS A. CARVER, a citizen of the United States, residing at Colo, in the county of Story and State of Iowa, have invented a new, original and ornamental Design for Dust-Pans, of which the following is a specification, reference being had to the accompanying drawing, forming a part thereof.

Figure 1 is a top perspective view of a dust pan showing my new and ornamental design. Fig. 2 is a side elevation on a re-

duced scale of my design for a dust pan. Fig. 3 is a perspective view of my design for a dust pan on a reduced scale viewing the same obliquely from the rear end thereof.

I claim:

The ornamental design for a dust pan, as shown.

THOMAS A. CARVER.
